US0D1088815S

(12) **United States Design Patent** (10) Patent No.: **US D1,088,815 S**
(45) Date of Patent: ** Aug. 19, 2025

(54) **MOUNTING PLATE**

(71) Applicant: **SPHERO, INC.**, Boulder, CO (US)

(72) Inventors: **Lindsey Cross**, Boulder, CO (US);
David Clarke, Lafayette, CO (US);
Bryan Hain, Boulder, CO (US)

(73) Assignee: **SPHERO, INC.**, Greenville, TX (US)

(**) Term: **15 Years**

(21) Appl. No.: **29/909,431**

(22) Filed: **Aug. 4, 2023**

Assistant Examiner — Elizabeth Sun Ko

(57) **CLAIM**

The ornamental design for a mounting plate as shown and described.

DESCRIPTION

FIG. 1 is a top perspective view of a mounting plate showing our new design.

FIG. 2 is a bottom perspective view of the mounting plate of FIG. 1.

FIG. 3 is a top view of the mounting plate of FIG. 1.

FIG. 4 is a bottom view of the mounting plate of FIG. 1.

FIG. 5 is a right side view of the mounting plate of FIG. 1.

FIG. 6 is a left side view of the mounting plate of FIG. 1.

FIG. 7 is a front view of the mounting plate of FIG. 1; and,

FIG. 8 is a rear view of the mounting plate of FIG. 1.

The broken lines depict portions of the mounting plate that form no part of the claimed design.

1 Claim, 7 Drawing Sheets
